UNITED STATES PATENT OFFICE

ALFRED C. GILBERT, OF NORTH HAVEN, CONNECTICUT, ASSIGNOR TO THE A. C. GILBERT COMPANY, OF NEW HAVEN, CONNECTICUT

CONSTRUCTION TOY

Original application filed May 26, 1927, Serial No. 194,374. Divided and this application filed December 11, 1929. Serial No. 413,236.

The present application is a division of my application Serial No. 194,374, filed May 26, 1927.

This invention relates to toy building sets used in the erection of buildings, bridges, etc., and in the construction of mechanical devices, such as gear boxes, tumbling barrels, and similar mechanical structures for association with the toys so built, or as individual toys. More particularly this invention relates to a combination of toy building elements, and in certain aspects thereof to the individual elements of the combination whereby mechanical devices may be constructed which are adapted to be operated by a toy electric motor or other power means, in order to more closely simulate the modern device which the toy is modeled from, and to give instruction and to create an interest in such construction to the toy builder and user.

The principal object of this invention is to provide a novel toy element, which is adapted for use in combination with another novel element to form a unit suitable for use in the construction of gear trains and the like.

Another object of this invention is to provide an element adapted for use in a mechanical device, and which may be readily assembled to other toy elements in various combinations therewith.

Another object of this invention is to provide an element which is adapted for use in combination with a gear blank or a disk, or a similar toy part or parts, to provide a hub or shaft bearing for the same, and which may be detachably secured thereto in various positions thereon for a variety of purposes.

Still another object of this invention is to provide a hub member adapted for use in various mechanical models and toys by being detachably assembled to other toy parts, cooperating portions and features of each assuring substantially accurate and convenient assembly therewith.

A further object of this invention is to provide a gear wheel or disk, in combination with a hub member of the desired form, the gear wheel or disk being readily detached from the hub member and adapted to be associated with or assembled to other elements and hub

members, cooperating parts of each assuring substantially accurate assembly of one element with respect to the other.

To these and other ends, the invention consists in the novel features and combinations of parts to be hereinafter described and claimed.

In the accompanying drawings:

Fig. 1 is a side elevation of a mechanical device in the structure of which elements embodying the features of this invention are used;

Fig. 2 is an end view of the device shown in Fig. 1;

Fig. 3 is an enlarged portional elevation of one end of the device shown in Fig. 1;

Fig. 4 is an enlarged end view of a part of the assembly shown in Fig. 1, certain parts having been removed for the sake of clearness;

Fig. 5 is an end view of a hub member embodying the features of this invention;

Fig. 6 is a side face view of a gear plate or blank embodying certain features of this invention;

Fig. 7 is an end view of a somewhat modified form of hub member;

Fig. 8 is an edge view of a hub member assembled to a pair of gear blanks or plates;

Fig. 9 is a section of the parts shown in Fig. 8;

Fig. 10 is an edge view of a somewhat different arrangement of hub members with a gear plate;

Fig. 11 is a section of the parts shown in Fig. 10;

Fig. 12 is still another arrangement of a hub member, with a disk-like plate;

Fig. 13 is an end face view of a hub member secured to a disk or end plate; and

Fig. 14 is a section on line 14—14 of Fig. 13.

The mechanical device selected to illustrate the features of my invention is a toy tumbling barrel. This tumbling barrel comprises a casing 10, in this instance made up of a plurality of curved plates, end members 11, and end plates or disks 12 and 13. The end plate or element 12, in this instance, is a disk somewhat similar to that illustrated

in Fig. 12, and which is provided with a relatively large central perforation 14. A hub element 15 is provided for the plate 12, through an opening in which hub members a shaft 16 passes, and is adapted to rotate freely therein, the set screw 17 of the hub being for that purpose disposed out of engagement with the shaft. The shaft 16 extends longitudinally through the casing 10 and beyond the outer end plate 13 thereof. Suitable supporting frames 18 and 19 are provided to support the shaft 16 at each end thereof. The frames 18 and 19 are constructed by assembling together various forms of toy building elements, such as perforated strips 20, perforated plates 21 and 22, and perforated bracket members 23. In this instance, one of the perforations in each of the plates 22 is used as a bearing for the end of the shaft 16 supported thereby.

The particular construction shown and the novel features of the casing 10, the end members 11, the end plates or disks 12 and 13, and the plate 21, form the subject-matter of co-pending applications, and further description thereof is unnecessary.

In order to impart rotary movement to the tumbling barrel, a train of gears is provided which may be drivingly connected to a motor 24. The train of gears includes a pinion 25 composed of two pinions in end abutment, having hub members 26 provided with suitable set screws 27, whereby they are secured to a short length of shaft 28. The shaft 28 extends through a perforation in the plate 21, and a pulley wheel 29 is secured to the outer end thereof. A suitable belt 30 extends about the pulley 29 and about a pulley 31, secured upon the shaft of the motor 24. The pinion 25 meshes with a gear 32, having a hub 33 secured to a shaft 34, which also passes through a perforation in plate 21. Another pinion 35, similar in structure to that of pinion 26, is secured in like manner to shaft 34 and meshes with a gear 36.

The gear 36 used in this instance is similar to that shown in detail in Fig. 6, and comprises a disk having gear teeth 37 formed on its periphery. The gear 36 is provided with a center opening 38, which is surrounded by a circular series of perforations 39, which in this instance are spaced apart peripherally at an acute angle of substantially 45° from each other. Spaced outwardly toward the periphery of the gear 36 from the perforations 39, and spaced, in this instance, at substantially 90° from each other, are other perforations 40. The perforations 39 are each radially spaced from the center opening 38, and the perforations 40 are each radially spaced from the adjacent perforation 39, a distance equal to the spacing between the perforations in other elements of the building toy.

The gear 36 is secured to the shaft 16 of

the tumbling barrel illustrated, by means of hub members 41. The hub member 41 comprises a sleeve portion 42 and a plate portion 43. This construction is shown in detail in Figs. 10 and 11. To provide a firmer support for the gear 36, upon the shaft 16, two hub members 41 are used, one being disposed on either side of the gear 36 with the plate portions 43 thereof in abutment therewith. The plate portions 43 of each hub member are provided with a circular series of perforations 44 that correspond in spacing and diameter to the perforations 39 of the gear 36. Securing means, such as bolts 45, are passed through these perforations to securely clamp the parts together. The sleeve portion 42 is secured to the plate portion 43 by passing a reduced end 46 of the sleeve portion through an opening in the center of the plate, and riveting or spinning over the reduced sleeve end upon the reverse side of the plate, as at 47. The portion 47 is pressed or flattened out into a substantially circular form and presents a shoulder 48 which is substantially of the same or slightly smaller diameter than the opening 38 in the gear 36, or the opening 14 in the disk 12. By the cooperation between the shoulder 48 and the material about either of the openings 38 or 14, the hub member 41 is located substantially at the center of the respective parts, gear 36 or disk 12. Clamp screws 17 are provided in the sleeve portions 42 for securing these parts to a shaft or the like, when such an operation is desired. The hub member 41 when used, as in Fig. 12, as a bearing bushing or support, as described above, may be assembled to the disk by inserting the sleeve portion 42 through the opening 14 therein, whereby the cooperation therebetween will locate the hub or bearing member 15 relatively to the disk.

In order to connect the casing 10 and end members 11 to the driving means to obtain rotating movement therefrom, the gear 36 is secured to the end plate or disk 13 by bolts 49. The bolts 49 pass through the openings 40 in the gear 36 and through corresponding openings or slots 50 in the disk 13, being secured thereto by a pair of nuts 51, one disposed on either side of the disk and threadingly engaging the bolt 49 to clamp the disk between them, as shown in Fig. 3.

Figs. 7, 8, 9, 13 and 14 illustrate a somewhat modified form of hub member 60, for use when a shaft of somewhat larger diameter is used in place of shaft 16. The hub member 60 comprises a sleeve portion 61 and a plate portion 62. The sleeve portion 61 is reduced in diameter at one end, and in the reduced portion a set screw 63 for securing a shaft thereto is provided. The other end of the sleeve portion is also reduced in diameter, and the reduced portion 64 is inserted through an opening 65 in the plate portion and riveted there and flattened as at 66. In

Figs. 8 and 9 the hub member 60 is shown secured by bolts 45 to a pair of gear members 36, with the flattened reduced end 66 of the hub member abutting the side surface of 5 one of the gears 36. In Figs. 13 and 14, the hub member 60 is shown secured by bolts 45 to a disk member 12^a, with the sleeve portion 61 extending through the opening 14^a therein, the diameters of both the opening and 10 this portion of the sleeve being substantially equal so that the cooperation thereof will tend to centralize one part relatively to the other.

The plate portion of the hub member 60 is 15 provided with perforations 44, which are disposed in a circular series therein, and like those in hub member 41 are spaced from the center opening thereof a distance equal to the spacing between the perforations in the 20 other toy building elements, such as the gear 36, disk 12, etc. The perforations 44 in both plate portions 43 and 62 are peripherally spaced apart at the same distance and the spacing corresponds to that of the other toy 25 building elements, such as the gear 36, disk 12, etc.

While I have shown and described a preferred embodiment of my invention, it will be understood that the same is not to be limited thereto in all of its details, as many modifications and variations are possible which will lie within the spirit of the invention and the scope of the appended claim.

What I claim is:

35 In a toy construction set having a plurality of elements provided with perforations spaced apart at a standard spacing common to the elements and including a flat disk-like member having a central opening and a circular series of perforations spaced according to the standard spacing and disposed about said opening, means for mounting said flat disk-like member upon shafts of varying sizes comprising a pair of hub members, each 40 of said hub members being provided with a plate portion having a circular series of perforations adapted to register with said first mentioned circular series of perforations, and each of said hub members having a hub 45 element secured to the plate portion thereof, the hub element of one of said members being adapted to be set within said central opening when said hub member is placed in one relation and secured to said disk-like member by 50 bolts passing through the registering perforations, to reduce the size of said central opening, and said hub element being adapted to project away from said disk-like member when the hub member is placed in another 55 relation and secured to said disk-like member by said bolts, and the other of said hub members being adapted to be abutted against the face of said disk-like member and the hub element thereof being provided with a 60 bore of substantially the same size as the 55

opening in said disk-like element and adapted to register therewith, the plate portions of the respective hub elements being adapted for simultaneous attachment to said disk-like member by fastening bolts common to 70 the two elements.

In witness whereof, I have hereunto set my hand this 9th day of December, 1929.

ALFRED C. GILBERT.
